UNITED STATES PATENT OFFICE.

FLORENCE A. STRIETER, OF CHICAGO, ILLINOIS.

RAILROAD-GATE.

1,245,661.

Specification of Letters Patent. Patented Oct. 30, 1917.

Application filed June 27, 1916. Serial No. 106,131.

To all whom it may concern:

Be it known that I, FLORENCE A. STRIETER, a citizen of the United States, residing at Chicago, in the county of Cook and State 5 of Illinois, have invented certain new and useful Improvements in Railroad-Gates, of which the following is a specification.

This invention relates to railway gates and particularly to that class of gates which 10 are used to obstruct the highway crossing a railroad at times when trains are approaching and crossing the highway.

It has been found that railway gates, or the supporting posts thereof, often form 15 undesirable obstructions to traffic; and not only are frequently injured by vehicles, but also vehicles, particularly automobiles, may become stranded against these supports and thus prevent closing of the gates, or they 20 may be unable to clear the railroad track in time to avoid injury by the train. Because of this, one of the objects of my invention is to provide a suitable gate which when open has no portion above the surface 25 of the highway. This arrangement also prevents any interference with the operation of the gate by sleet, hail, snow, or ice; and prevents injury to the gate or the mechanism by the elements.

30 It has also been found that railway gates are sometimes run into by vehicles as they are being closed, thus, perhaps, preventing the vehicle from escaping the train. In view of this, one of the objects of my invention is to provide a gate which will be forced 35 out of the way of vehicles if it has not been closed too far, and hence the danger of injury is reduced.

Other objects of the invention will be 40 apparent from a consideration of the following description thereof.

Of the accompanying drawings, Figure 1 is a reduced plan-view of a railroad crossing, a highway, and of a gate which I provide 45 for obstructing the highway at the proper time. Fig. 2 is a section along the line 2—2 of Fig. 1 illustrating the gate and operating mechanism which embody the features of my invention. Fig. 3 is a plan-view of the gate and operating mechanism showing diagrammatically the electric means used for operating the mechanism. Fig. 4 is a detail diagrammatic illustration of the electric means. Fig. 5 is a sectional view 55 of the gate and the operating mechanism along the line 5—5 of Fig. 2. Fig. 6 is an

enlarged detail view of a certain feature of the mechanism.

In general the invention comprises a chamber 8 beneath the highway 9 which is 60 crossed by the railroad 10. The walls 11 of the chamber are made of any suitable material such as cement, and have suitable inlets for the entrance of repair men or for other purposes. Slidably mounted in the posts 12, which are inclosed and vertically supported in the chamber 8, is the gate 13, the upper plate 14 of which, when the gate is down or open rests upon the surface of the highway and closes the opening 15 in the highway 70 through which the gate is elevated. Gear racks 16 form a portion of the frame of the gate and are arranged to slide vertically in the guiding posts 12. A central rack 17, forming also a portion of the frame of the 75 gate, may be used if the gate is of sufficient length to warrant. When the gate is open no portion thereof projects above the surface of the highway. Supports for lights, bells or other signals may be used, however, 80 in any ordinary or suitable manner.

The operating mechanism of the gate comprises gear-wheels 18, mounted on a shaft 19 journaled in brackets 20. Fixed to one end of the shaft 19, is a gear-wheel 21, 85 meshing with a pinion 22, which is mounted on the shaft of the operating motor 23. The gear wheels 18 mesh with the respective racks 16 and 17 and, when the motor is operated in the proper direction, the gate will 90 be raised to the position desired.

Suitably mounted adjacent the railroad track 10, are electric switches 26 and 27, arranged to be closed in an ordinary manner by the wheels of the train as it approaches or leaves the highway; and properly connected to these switches are electric conductors which are connected in a suitable manner to the motor 23, as is more fully described hereinafter.

In practice when the front wheels of the approaching train reach switch 26, the switch will be closed and the motor will be set in operation rotating in the proper direction to elevate the gate; the gate will be 105 elevated until the bottom ends of the racks pass slightly above the shaft 19; and the gate, by means hereinafter described, will be held in such position with the racks clear of the gear wheels 18 the gear wheels running idle until the supporting means are released. When the front wheels of the train 110

reach switch 27, the motor will be reversed, the supporting means referred to will be withdrawn, and the racks, due to the weight of the gate, will be forced downwardly in mesh with the gear-wheels, and the motor will draw the gate downwardly to normal position. When the gate is lowered to normal position, the lower portion thereof will open a switch 30, which will open the operating circuit and stop the motor. Suitable weights may be used to assist in forcing the gate downward, if desired.

Fig. 4 shows diagrammatically the electric means used for operating the motor. The starting switch 26 is normally held open by means of a spring 60; and when closed and the motor is in operation is held closed by the electro-magnet 61. The reversing switch 27 is normally held in the position shown by the spring 62 and is held in the reversed position by the electro-magnet 63. The stopping switch 30 is normally held open by the bottom of the gate; and is closed when the gate is elevated by the spring 64. In the diagram the source of electric energy is indicated by 65, the field coils of the motor by 66 and the armature coils by 67. Switches 26 and 27 are held in position against the force of the respective springs 60 and 62 by the armature current, and switch 26 also by the field current; but the field current alone is too weak to hold the switch 26 in position against its spring and the armature current cannot shift switch 27 against the spring. By tracing out the circuits, it will be seen that, when switch 26 is closed, the current passes from the battery 65 to the field coils 66, through the electro-magnetic coil 61, switch 26, and back to the battery; and it also passes from the battery through the connecting wires to switch 27, to the armature coils 67, back through the other branch of the switch 27, through the electro-magnetic coils 63 and 61, and through switch 26 back to the battery. Hence as soon as switch 27 is reached by the train this switch will be shifted, will be held in the shifted position by the coil 63, and the motor will therefore be reversed in direction and will so continue until switch 30 is opened by the descending gate, when the electro-magnet 61 will be de-energized and switch 26 will be opened.

In order to keep the electro-magnets 61 and 63 energized when switch 27 is shifted, the blades of the switch are so constructed as to short the contacts as the blades are shifted, and the coils of the magnets prevent a dangerous flow of current through the shorted circuit.

The motor is of such power as to lift the gate easily but not to prevent the gate being forced downwardly by an automobile running over the top before the gate has been raised a very material distance. The

front wheels of the automobile will force the top down or at least delay its movement sufficiently to allow the rear wheels to pass over. If the gate has risen too far to be run over by the wheels, it will ordinarily be plainly seen by the operator of the automobile, and if run into it will merely stop the automobile. The electromagnetic coils are designed so as to provide sufficient resistance to prevent injury to the armature coils by a large flow of current even though the armature, as the gate is forced downwardly, is rotated in a reverse direction.

The means which I have provided for holding the racks 16 and 17 out of mesh of the gear wheels 18 when the gate is elevated to its highest position, comprises a block 33, fixed to the bottom of the rack 16 adjacent the gear-wheel 21, and a pawl 34, pivoted to the supporting post. The pawl by means of a spring 35, is forced under the block 33, when the racks are elevated to the maximum position, and thus holds the racks in such position. The bottom of the block 33 is beveled, as shown in Fig. 5, so as to support the block in the highest position as the upper end of the pawl turns inwardly. By this arrangement, it will be seen that the gate, when supported by the pawl, is entirely disconnected from the elevating means and is free to be lifted out of the guiding means and entirely removed therefrom. Hence in case of breakage, or any need of repairs, or in case of inoperativeness of the elevating means, the gate may be readily removed for repairs or to allow traffic to pass.

In order to release the pawl when the motor is reversed, I provide a finger 37, fixed to the gear-wheel 21, and so positioned thereon that the outer end of a member 38, will lie in the pathway of the finger as the finger rotates with the gear-wheel 21. The member 38 is pivoted to the outer end of an arm 39 fixed to the pawl 34. As the gear-wheel rotates in the direction required to elevate the gate, the member 38 will be turned backwardly by the finger 37 as the two come in contact. But the spring 41 will force the member back to normal position when the finger passes, and, as the gear 21 is reversed in direction, a stop 40 will prevent the member 38 being pushed aside by the finger 34, and the arm 39 will be driven outwardly, and this in turn will force outwardly the pawl 34, releasing the block 33 and allowing the racks to descend and mesh with the gear-wheels 18.

Although I have described with much particularity the various details of the mechanism which I prefer for carrying out the purpose of my invention, yet it will be evident that persons skilled in the art could make modifications therein without departing from the spirit of my invention, as disclosed by the following claims. And it is

to be understood that the gates may be placed each side of the railway track, the two being operated by the same switches; and switches may be inserted to operate 5 when the train is moving in either direction on the same track or on a double track.

I claim as my invention:

1. The combination of a railroad-track crossing gate, an electric motor, operating 10 means connecting said gate with said motor, a circuit for operating said motor, a switch in said circuit adjacent the railroad track and adapted to be closed by the wheels of a train, resilient means tending to hold said 15 switch open, an electromagnet with its coil in said circuit adapted to hold said switch closed when said circuit is energized, a reversing switch in said circuit adapted to be operated by the wheels of a train on said 20 track, resilient means tending to hold said reversing switch in one position, and an electromagnet with its coil in said circuit adapted to hold said reversing switch in another position when said circuit is energized; a 25 third switch in said circuit adapted to be operated by said gate, resilient means tending to hold said third switch closed, said third switch being opened when said gate is opened.

2. The combination of a railroad track crossing gate, an electric motor, means connecting said gate with said motor, a circuit for operating said motor, a switch in said circuit adjacent the railroad track and adapted to be closed by the wheels of a train, resilient means tending to hold said switch open, an electromagnet with its coil in said circuit adapted to hold said switch closed when said circuit is energized, a reversing switch in said circuit adapted to be operated by the wheels of a train on said track, resilient means tending to hold said reversing switch in position to operate the motor to raise the gate, an electromagnet 45 with its coil in said circuit adapted to hold said reversing switch in position to lower the gate when said circuit is energized; means associated with said track for moving said reversing switch from the former to the latter position; a third switch in said circuit adapted to be operated by said gate, and resilient means tending to hold said third switch closed, said gate when opened adapted to open said third switch. 50

3. The combination of a gate; a frame for holding said gate; means for elevating said gate comprising a rack and a coöperating pinion; means for supporting said gate comprising a block fixed to said rack, a pawl pivoted to said frame adjacent said rack, resilient means for forcing said pawl beneath said block when said rack is raised by said pinion to the maximum elevation, and means for removing said pawl from beneath said block. 55

4. The combination of a gate; a frame for holding said gate; a motor for operating said gate; a rack and gear connecting said motor with said gate; means for supporting said gate in its maximum elevation comprising a block fixed to said rack, a pawl pivoted to said frame, and resilient means for forcing said pawl beneath said block when the lower tooth of said rack is elevated by said pinion above said pinion; and means for removing said pawl from beneath said block when said motor is reversed, said means comprising a finger fixed to said pinion, said pawl when beneath said block being in the path of motion of said finger. 60

5. The combination of a gate, means for elevating said gate, means for supporting said gate in its highest position, means for starting said elevating means, means for stopping said elevating means, and means operated by said elevating means for withdrawing said supporting means. 85

6. The combination of a railroad - track crossing gate normally mounted underneath the track adjacent said crossing for movement above the surface of the ground, an electric motor, a rack and gears connecting said gate with said motor, a circuit for operating said motor, a switch in said circuit adjacent the railroad track and adapted to be closed by the wheels of a train, resilient means tending to hold said switch open, and an electromagnet with its coil in said circuit adapted to hold said switch closed when said circuit is energized, a reversing switch in said circuit adapted to be operated by the wheels of a train on said track, resilient means tending to hold said reversing switch in one position, an electromagnet with its coil in said circuit adapted to hold said reversing switch in another position when said circuit is energized; a third switch in said circuit adapted to be operated by said gate, resilient means tending to hold said third switch closed, and said third switch being opened when said gate is opened. 100

7. The combination of a railroad - track crossing gate normally mounted underneath the track adjacent said crossing for movement above the track, an electric motor, a rack and gears connecting said gate with said motor, a circuit for operating said motor, a switch in said circuit adjacent the railroad track and adapted to be closed by the wheels of a train, resilient means tending to hold said switch open, and an electromagnet with its coil in said circuit adapted to hold said switch closed when said circuit is energized, a reversing switch in said circuit adapted to be operated by the wheels of a train on said track, resilient means tending to hold said reversing switch in one position, an electromagnet with its coil in said circuit adapted to hold said reversing switch in another position when said circuit is en- 115 120 125 130

ergized; a third switch in said circuit adapted to be operated by said gate, resilient means tending to hold said third switch closed, said gate when opened adapted to open said third switch, means for supporting said gate in its highest position, and means for withdrawing said supporting means when said reversing switch reverses said motor.

10. The combination of a railway-crossing gate, vertical guiding means, elevating means, and supporting means; all of said means being operatively associated with said gate, but being disconnected from said gate when said gate is raised, whereby said gate may be freely removed from all of said means.

9. The combination of a railway-crossing gate, vertical-guiding means, associated with 20 said gate, elevating means, means normally connecting said gate with said elevating means, said connecting means being entirely

disconnected from said gate when said gate is raised, means for supporting said gate when said gate is raised, and means operated by said elevating means for withdrawing said supporting means when said elevating means is operated to lower said gate.

10. The combination of a railway crossing gate, vertical guiding means associated with 30 said gate, elevating means, means normally connecting said gate with said elevating means, said connecting means being entirely disconnected from said gate when said gate is raised, and means for supporting 35 said gate when said gate is raised, said gate when closed resting on but otherwise being disconnected from said supporting means, whereby said gate when closed may be freely elevated in said guiding means and 40 freely removed therefrom.

In testimony whereof, I hereunto set my hand.

FLORENCE A. STRIETER.
